CLAIM

The ornamental design for an electronic thermometer, as shown and described.

DESCRIPTION

FIG. 1 is a front elevational view of an electronic thermometer probe showing our new design;

FIG. 2 is a top plan view, the bottom plan view being identical;

FIG. 3 is a rear elevational view;

FIG. 4 is a left side elevational view;

FIG. 5 is a right side elevational view; and

FIG. 6 is a cross-sectional view taken along line 6—6 of FIG. 1 thereof.

FIG. 1

FIG. 2

FIG. 3

FIG. 4

FIG. 5

FIG. 6
